ELECTRICAL CONTROL MECHANISM FOR
DRIVE MEANS IN ADDRESS PRINTING
MACHINES

Fernand Usselmann, Sceaux, France

Application April 18, 1955, Serial No. 502,086

Claims priority, application France April 24, 1954

13 Claims. (Cl. 192—116.5)

This invention relates to electrical control mechanism which is intended for use in a case where two or more shafts must be driven by a common drive shaft in a certain relative angular position.

The object of this invention is to provide a control mechanism by which when the drive connection to one or other or both of the driven shafts has been interrupted, drive will be re-established automatically with the driven shafts in the proper angular relationship.

Such a problem arises, for example, in addressing machines which all comprise two principal mechanisms, one the mechanism for the feed of the address-plates and the other the printing mechanism: it is necessary to actuate one or the other of these mechanisms or both together, in order to be able to bring about the following operations:

(a) Feed without printing either to bring the first plate into the printing position, or to carry out a visual or automatic selection of the address-plates.

(b) Printing without feed in order to effect a repetition of the address for example

(c) Printing and feed in order to print a series of successive addresses.

It is necessary, in order to obtain correct functioning of the addressing machine, that the shafts of the feed and printing mechanisms shall be situated in the same relative angular position every time.

The invention is concerned with cases in which the problem of maintaining two or more driven parts receiving drive from a driving shaft in a certain angular relationship arises.

The main object of this invention is to provide a control arrangement by which such operating conditions as those referred to can be automatically obtained.

In carrying out the invention an electro-magnetically controlled coupling between a driven shaft and the driving shaft is effective for a number of defined positions on the driving shaft.

The arrangement comprises also a locking device capable of holding the coupling in a disengaged position so long as the locking device is not released, the release of the locking device permitting coupling to take place under the action of an electrical impulse delivered to a control electro-magnet.

In addition, the driven shaft comprises means to return the locking device to the locking position.

The mechanism comprises two or more driven shafts each provided with such an electro-magnetically controlled coupling and for simultaneous coupling to the driven shafts the closure of the feed circuit of each of the electro-magnets is effected in a permitted zone such that the circuit is broken before and after the theoretical engagement point for each defined engagement position of each driven shaft; the permitted zone provides a margin sufficient to take into account the mechanical and electrical characteristics of the whole of the mechanism while still ensuring that the drive is effected for the first defined engagement position.

2

For successive couplings, the closure of the circuit of each electro-magnet controlling the engagement is permitted once only per revolution in the permitted zone preceding the theoretical engagement point.

- 5 More particularly the drive shaft can drive a switch control member which ensures the closure of a switch for each defined engagement position in the permitted zone, while each driven shaft drives a switch control member which ensures the closure of a switch in a zone which, 10 when the drive and driven shafts are in the required angular synchronism, covers at least a part of the permitted zone and extends beyond the theoretical engagement point by a distance sufficient to ensure contact when the mechanism is disengaged, without covering the neighbouring permitted zone, the afore-mentioned switches being disposed in series in relation to each electro-magnet controlling the engagement of the coupling.

As applied to an addressing machine, the two shafts concerned would be the plate feed shaft and a printing shaft, these shafts being capable of being driven, either separately or simultaneously, by a common drive shaft each, through the intermediary of a coupling device of this invention. Such an application is shown in the accompanying drawings.

- 25 Other features and advantages of the present invention will appear from the description which will follow with reference to the accompanying drawings which show by way of example one embodiment of the present invention.

In these drawings:

- 30 Figure 1 is a cross-section of a coupling between a drive shaft and a driven shaft;

Figure 2 is a section on the line II—II, Figure 1;

- Figure 3 is a section similar to Figure 2, but applied to a mechanism comprising a drive shaft and two driven shafts;

Figure 4 is a circuit diagram capable of being used for the control of the mechanism represented in Figure 3;

- Figure 5 is a section on the line V—V, Figure 3, and Figure 6 is a diagram showing the closing time of the contacts effecting the closure of the engagement-control electro-magnets.

Referring to Figure 1, the coupling device according to the invention is provided to enable driven shaft 1 to be driven by a drive shaft 2. The latter is driven, for example by means of a pulley 3 and a belt (not shown), by a motor (not shown) such as an electric motor.

On the drive shaft 2 is keyed a pinion 4 meshing with a toothed wheel 5 loose on the driven shaft 1. A ratchet wheel 6 is secured to the wheel 5, the ratchet having for example four teeth which can engage a pawl 7 carried by a plate 8.

The pawl 7 is normally held out of engagement by a latch 9, which is drawn into the withdrawn position by a spring 10, but is held in the engaging or locking position by a small pawl 11. This pawl 11, which can pivot about a pin 12, is drawn by a spring 13 towards the locking position. One of the arms of the pawl 11 either constitutes the armature of an electro-magnet 14, as is shown, or is connected mechanically to the armature.

- 60 The plate 8 has a part 15 which forms a cam upon which bears the end of one arm of a bell-crank lever 16 urged by a spring 17 against the cam plate. The end of the other arm of the bell-crank lever 16 carries a stop 18 against which can bear a pin 19 carried by the latch 9 when the latter moves into the withdrawn position.

65 The operation of the coupling device which has been described is as follows:

In the rest position, the latch 9 is retained by the pawl 11 in the locking position, the pawl 7 bearing on the latch 9.

To effect engagement, a momentary electrical impulse is transmitted to the electro-magnet 14. The armature

of the electro-magnet is moved so that pawl 11 turns in a counter-clockwise direction and frees the latch 9 which is drawn into the withdrawn position by its spring 10. The pawl 7 is thus freed and swings into engagement with the first of the teeth of ratchet wheel 6 to pass. The driven shaft 1 is thus driven.

At the same time, the pin 19 of the latch 9 has moved into contact with the stop 18 on the lever 16, so that when the cam 15 rides over the end of the bell-crank lever 16 and turns it in a clockwise direction, the stop 18 returns the latch 9 into the locking position against the action of the spring 10.

The action of the electro-magnet 14 having ceased, the pawl 11 again retains the latch 9 in the locking position. Under these conditions, the pawl 7 again encounters the bolt after one revolution of the driven shaft 1 so that the pawl 7 is disengaged from the ratchet wheel 6. The coupling between the driving shaft 2 and the driven shaft 1 is thus broken and the shaft 1 is stopped.

In order to maintain the driven shaft 1 in the stopped position there is provided a counter-pawl 20 (shown in Figure 5) which opposes rotational movement in the opposite direction; rotational movement in the normal direction is prevented by a stop 21 against which the pawl 7 bears.

In order to cause the driven shaft 1 to make several revolutions without disengagement, it is sufficient either to maintain the circuit of the electro-magnet 14 closed, or to close this circuit momentarily before each movement of the pawl 7 to the latch 9 so as to cause the latter to move aside in time from the path of the pawl 7.

Provision is made to enable two or more mechanisms to receive their movement from one and the same driving shaft through the intermediary of couplings which must operate in angular synchronism (i. e. without shifting) by a fraction of a revolution or even a complete revolution, either on simultaneous engagement of the whole or of a part of the mechanisms, or on successive engagements of mechanisms individually or in groups. This angular synchronisation is brought about in the manner which will be described with particular reference to Figures 4 and 6 which relate to the particular case of two driven shafts which may for example be the shaft for control of the feed mechanism and the shaft for control of the printing mechanism in addressing machines.

For simultaneous engagement, the closing of the feed circuit of each of the control electro-magnets such as the electro-magnet 14 in Figure 1 is permitted in a zone (which will be referred to as the permitted zone) such that the circuit is broken before and after the theoretical engagement point at each passage of a tooth of the ratchet wheel 6 in Figure 1 past this point, with a margin which while being sufficient to take into account the mechanical and electrical characteristics of the assembly, ensures that the drive is imparted by the first tooth to pass. These permitted zones have been indicated in the diagram in Figure 6 by the segments *a* representing the parts of a rotation of the drive shaft where a contact in series with the electro-magnet 14 is closed, the aligned arrows *a'*, *b*, *b'* representing the theoretical point of engagement.

For the successive engagements, the closing of the circuits of the electro-magnets such as 14 is permitted once only per revolution in the permitted zone as defined above, preceding the theoretical engagement point. As is seen from Figure 6, the drive shaft for the ratchet wheel 6 establishes contact in the permitted zone defined above by the segments *a*.

Furthermore, each driven shaft also establishes a contact over a part of a revolution of the driven shaft as represented by the segment *b* in Figure 6, this part of a revolution being such that, when the drive shaft and the driven shaft are in angular synchronism, the angular zone corresponding to the segment *b* covers at least part of the angular zone corresponding to the segment *a* and ex-

tends beyond the theoretical engagement point (*a'*—*b'*) by a distance sufficient to ensure contact when the mechanism is disengaged, without however covering the angular permitted zone corresponding to the adjoining segment *a*.

These two conditions are fulfilled due to the electrical control shown in the diagram of Figure 4.

As is seen, the drive shaft 2 closes by means which will be described hereinafter, a switch 21 in the permitted zone defined by the segments *a* in the diagram according to Figure 6.

Each driven shaft 1 and 1a closes a switch 22 or 22a in angular zones defined by the segments *b* in this same diagram, these angular zones being as is seen in Figure 6 such that when the drive shaft and the driven shaft 1 or 1a are in angular synchronism, it covers all or part of the corresponding permitted zone *a* and extends beyond the theoretical engagement point by a distance sufficient to ensure contact when the corresponding mechanism is disengaged without extending into the following permitted zone.

The switches 21, 22 and 22a are connected in series with a main or master control switch 23 for the electro-magnets 14 and 14a, which master switch can be closed by a pedal 24. Each electro-magnet can be connected or isolated by a switch 25 or 25a.

26 indicates a main switch and 27 indicates a motor driving the drive shaft 2 by means of the pulley 3 (as shown in Figures 1 and 2).

The operation of the electrical arrangement is as follows:

In the case where simultaneous engagement of the coupling mechanisms of the two driven shafts 1 and 1a is required, the electro-magnets 14 and 14a are connected in circuit by the switches 25 and 25a.

After the closing of the master switch 23, the switches 22 and 22a connected to the driven shafts 1 and 1a themselves being closed in the disengaged position, the feed circuit will be closed by the closing of the switch 21 controlled by the drive shaft 2 and the two mechanisms will connect simultaneously.

In the case of successive engagements i. e. when one of the two mechanisms is already in continuous movement, the master switch 23 being permanently closed.

In order to actuate that one of the mechanisms which is at rest, it is sufficient to close its switch 25 or 25a. The feed circuit of the corresponding electro-magnet 14 or 14a of the said mechanism will now be closed when the switch 21 operated by the drive shaft 2 and the switch 22 or 22a operated by the corresponding driven shaft 1 or 1a are closed simultaneously. The closure of the circuit will necessarily occur in the permitted zone preceding the theoretical engagement point (see the diagram in Figure 6) and the angular synchronism will be ensured.

The closure of the switches 21, 22 and 22a takes place in the following manner (see Figures 3 and 5):

The switch 21 is closed by a cam 28 fast with a toothed wheel 29 meshing with a pinion 30 secured to the shaft of the pulley 3 driven by the motor 27.

The switch 22 (as is seen in Figure 5) is closed by a cam 31 fast with a toothed wheel 32 meshing with a toothed wheel 33 secured to the driven shaft 1.

The switch 22a would be closed in the same manner as has been shown for the switch 22 by the movement of the driven shaft 1a driving a pinion 33a (see Figure 3) similar to pinion 33 and acting in the same manner.

The electro-magnetic coupling device of this invention is applicable especially, although not exclusively, to addressing machines which comprise a feed mechanism for the address-plates and a printing mechanism.

As is known, in addressing machines a table is provided above which there are placed the two slideways in which the address-plates move. These are piled in a feed magazine. A shuttle, to which a reciprocating movement is imparted, pushes the address-plates one by

one into the slideways and causes them to pass over the printing head constituted by a piece of place or cylindrical flexible material inked by an appropriate device. On passing from the slideways the address-plates are piled in a reception magazine.

The printing head is mounted on a transverse rocking shaft supported by a bearing at each end. These bearings are spaced so as to provide the necessary width for the passage of the documents below the printing head. A transverse bridge, similarly of corresponding width, serves as support to one or more intermediate bearings for the rocking shaft. It can also carry the inking, listing, selecting, ejecting, counting, etc., devices. The bridge and the end bearings can be in one single piece or composed of assembled or unassembled elements.

In the application of the invention to such a machine the control shafts 1 and 1a are employed for the printing and feed mechanisms for the address-plates and these shafts are placed under the table on either side of a drive wheel 34 (as is shown in Figures 3 and 5), which can, in order to simplify construction, rotate freely with the ratchet wheels 6 and 6a, with which it is fast, on the shaft 1 or the shaft 1a; this drive wheel driving these shafts by means of synchronised couplings as have been described. These shafts are carried by bearings 35 and 35a fixed under the table indicated at T and are connected respectively to the printing head and the shuttle by any convenient method such as eccentric, cams or crank-plates, connecting rods, levers and shafts.

Thus a cam (not shown) placed on the control shaft of the printing mechanism can be provided to cause the lifting of a counter-pressure part at each descent of the printing head in order to bring the document against the address-plate. This counterpart can comprise an elastic compensating device permitting the printing of documents of greatly differing thicknesses, or documents piled under the printing head, the document placed on the upper part being withdrawn after each impression. The drive wheel 34 is driven by the electric motor 27 by means of pulleys and gears giving the appropriate transmission ratio. The control ratchet wheels 6 and 6a are keyed in the same angular position, the drive wheel 34 being placed between the two ratchet wheels 6 and 6a.

The connection between the drive wheel 34 and the ratchet wheels can be either rigid or elastic or frictional if it is necessary to absorb the shock at the moment of engagement, the ratchet wheels always being secured in the same angular position.

The switch control parts 30, 29, 28 and 21 positively connected with the ratchet wheels, operate in the safety zones a defined previously with reference to the diagram of Figure 6. If the connection between the drive wheel 5 and the ratchet wheels 6 and 6a is rigid, the control of the switch can be taken, as represented, from the shaft carrying the control pinion 4 of the drive wheel 5. A plurality of switches 21 in parallel, controlled by cams similar to cam 28 and suitably disposed, can be used to diminish their frequency of operation, the essential being to obtain a contact in the permitted zones between each passage of the teeth of the ratchet wheel 6 or 6a.

For each of the two driven shafts 1 and 1a there is the switch control parts 33, 32, 31 and 22 establishing contact in the angular zone b defined with reference to the diagram in Figure 6. The addressing machine is controlled by means of the pedal 24 closing the switch 23 (see Figure 4) in the pressed-down position and opening it in the rest position. This switch is placed in the feed circuit of the electro-magnets 14 and 14a for controlling the feed of the address-plates and for the print-

The machine has a control panel which carries the operating switches: the master switch 26 feeding the motor 27 and the circuits of the electro-magnets 14 and 14a controlling the engagements and the two switches 25 and 25a respectively for the circuits of the electro-

magnets 14 and 14a controlling the mechanisms for feed of the address-plates and for printing.

The operation of the parts is as follows:

5 The master switch 26 is placed in the "operation" position to actuate the electric motor 27 and feed the circuits of the electro-magnets 14 and 12a and the additional devices if necessary: the switch 25 for feed of the address-plates is placed in the "operation" position: the control pedal 24 is pressed down, which closes the contact 10 23, until the first address-plate is placed in the printing position and the printing switch 25a is placed in the "operation" position. The machine is now ready to print a different address-plate at each cycle.

In order to print an address, the document is placed 15 under the printing head, the pedal 24 pressed down during the time necessary for the engagement of the couplings.

In order to pass an address-plate without printing (sight selection), the printing switch 25a is placed in the 20 "stop" position before the pedal 24 is pressed down. In order to print the same address-plate a number of times (repetition), the feed switch for the address-plates, 25, is placed in the "stop" position before the pedal 24 is pressed down.

25 With the mechanism which has been described it is possible to effect, in a simple manner, the different operations desirable in an addressing machine, especially the following operations:

- 30 (1) Automatic positive or negative selection,
- (2) Automatic repetition,
- (3) Continuous operation,
- (4) Automatic stopping at each selected impression,
- (5) Automatic stopping after a predetermined number of impressions,
- (6) Automatic cut-off of continuous documents after a predetermined number of impressions.

The electro-magnetic control device of this invention with its angular synchronisation of driven shafts can be used in cases other than that of addressing machines. It can, for example, be applied to machines comprising more than two driven shafts (as has already been contemplated in the description given). It is sufficient to provide one coupling per driven shaft and as many control electro-magnets as there are driven shafts, these electro-magnets being arranged in parallel and each comprising a selection switch such as 25 or 25a, with as many switches such as 22 and 22a disposed in series with the switch 21 controlled by the drive shaft.

It is further apparent that in place of using couplings 45 constituted by ratchet wheels and pawls it would be possible to use dog-clutch arrangements or any other devices ensuring a positive connection.

What I claim is:

1. In a control mechanism to establish drive connection between a rotatable driving part and at least two rotatable driven parts which are required to have a fixed relative angular position, the combination of a drive coupling for each driven part, each coupling being arranged for drive connection with the driving part only in defined angular positions of the driving part, an electromagnet to control each coupling part, a switch to prepare the circuit of each electromagnet, a cam driven by each driven part and formed to operate the switch in a zone extending about the theoretical point of register of the associated driven part, and a second switch to complete the prepared circuit, and a cam to operate the second switch in a zone related to a defined angular position of the driving part.

2. In a control mechanism to establish drive connection between a rotatable driving part and at least two rotatable driven parts which are required to have a fixed relative angular position, the combination of a drive coupling for each driven part, each coupling comprising a component movable on its driven part between coupling and non-coupling position, a holding member to hold the

coupling component in non-coupling position, an electromagnet to render the holding member inoperative to release the coupling member for coupling engagement with the driving member in one of its defined angular positions, and switches controlled by the driven parts and by the driving part to energise the associated electromagnet in zones extending about the theoretical point of angular position of the driven parts and related to the defined angular positions of the driving part.

3. In a control mechanism to establish drive connection between a rotatable driving part and at least two rotatable driven parts which are required to have a fixed relative angular position, the combination of a drive coupling for each driven part, each coupling comprising a component movable on its driven part between coupling and non-coupling position, a holding member to hold the coupling component in non-coupling position, an electromagnet to render the holding member inoperative to release the coupling member for coupling engagement with the driving member in one of its defined angular positions, switches controlled by the driven parts and by the driving part to energize the associated electromagnet in zones extending about the theoretical point of angular position of the driven parts and related to the defined angular positions of the driving part, and means operated in each rotation of a driven part to re-set the holding member.

4. In an addressing machine, in combination a driving shaft having defined drive engagement positions at which driven shafts are operatively engaged by it, at least two driven shafts capable of being selectively driven successively and simultaneously and to be maintained in angular synchronization, a positive coupling for each driven shaft, each coupling being such as to make coupling engagement between the driving shaft and a driven shaft only at one of the defined positions, electromagnets controlling the operation of each coupling, first means operated by said driving shaft for selectively energizing the electromagnets controlling the couplings of the shafts to be driven, said electromagnets being adapted to be energized in authorization permitted angular zones and to be de-energized in predetermined zones arranged between said authorization zones on each side of said defined engagement positions, second means operated once only in each revolution by each driving shaft for energizing the respective electromagnets controlling the couplings of the shafts to be driven after at least one of the driven shafts has been set in rotation only in a synchronization permitted zone extending about a selected common synchronizing engagement point at which the driving shaft operatively engages each shaft to be driven from a rest position.

5. In an addressing machine the combination according to claim 4, in which said first means comprises a first switch and said second means comprises for each driven shaft a second switch and in which the driving shaft effects the closure of the first switch for each defined engagement position of the driving shaft in said authorization zones, and in which each driven shaft effects the closure of its associated second switch in said synchronization zone which extends beyond the selected common synchronizing engagement point and which when the driven shafts are in angular synchronism extends at least over a part of one of said authorization zones of the driving shaft without overlapping the following authorization zone of the driving shaft, said first and second switches being connected in series with one another and with each electromagnet.

6. In an addressing machine comprising a control mechanism to establish drive connection between a rotatable driving part and at least two rotatable driven parts which are required to have synchronized angular rotation, the combination of a positive coupling for each driven part, each coupling making drive connection with the driving part only in defined angular positions of the driving part.

driving part, and electrical means for each coupling governed by the angular position of the driven parts in rotation to render each coupling operative when driven parts already in rotation are in a predetermined angular position relative to one of the defined positions of the driving part.

7. In an addressing machine comprising a control mechanism to establish drive connection between a rotatable driving part and at least two rotatable driven parts which are required to have synchronized angular rotation, the combination of a positive coupling for each driven part, each coupling being arranged for drive connection with the driving part only in defined angular positions of the driving part, electromagnets to control each coupling part, circuits connected to energize the electromagnets, switch means operated by each driven part to close the circuit of each electromagnet through a synchronization zone which extends beyond a selected common synchronizing engagement point of the associated driven parts and switch means operated by the driving part in authorization zones corresponding to said defined angular positions to complete said circuits when said driving part reaches a position corresponding to the first encountered authorization zone with all the driven parts at rest, and when said driving part reaches the same authorization zone if a driven part has already been set in rotation and means to initiate at will the driving of one of said driven parts prior to the driving of the other driven parts.

8. In a control mechanism to establish drive connection between a rotatable driving part and at least two rotatable driven parts which are required to have synchronized angular rotation, the combination of a drive coupling for each driven part, each coupling being arranged for drive connection with the driving part only in defined angular positions of the driving part, electromagnets to control each coupling part, circuits connected for selective energization of the electromagnets, a switch for opening and closing each circuit of each electromagnet, a cam driven by each driven part and formed to close the switch once each revolution in a zone extending about a selected common point for engagement of the associated driven parts, and another switch to complete each circuit, and a cam driven by the driving part to close said other switch in zones corresponding to said defined angular positions of the driving part.

9. In a control mechanism to establish drive connection between a rotatable driving part and at least two rotatable driven parts which are required to have a fixed relative angular position, the combination of a drive coupling for each driven part, each coupling making drive connection with the driving part only in defined angular positions of the driving part, electrical means for each coupling governed by the angular position of the driven parts to render each coupling operative when the driven parts are in a predetermined angular position relative to one of the defined positions of the driving part, and means to render each drive coupling inoperative in each rotation of the driven part.

10. In a control mechanism to establish drive connection between a rotatable driving part and at least two rotatable driven parts which are required to have a fixed relative angular position, the combination of a drive coupling for each driven part, each coupling comprising a component movable on its driven part between coupling and non-coupling position, a holding member to hold the coupling component in non-coupling position, an electromagnet to render the holding member inoperative to release the coupling member for coupling engagement with the driving member in one of its defined angular positions, and switches controlled by the driven parts and by the driving part to energize the electromagnets in zones extending about a theoretical point of engagement of the driven parts and corresponding to the defined angular positions of the driving part.

11. In a control mechanism to establish drive connection between a rotatable driving part and at least two rotatable driven parts which are required to have a fixed relative angular position, the combination of a drive coupling for each driven part, each coupling comprising a component movable on its driven part between coupling and non-coupling position, a holding member to hold the coupling component in non-coupling position, an electromagnet to render the holding member inoperative to release the coupling member for coupling engagement with the driving part in one of its defined angular positions, switches controlled by the driven parts and by the driving part to energize the electromagnets in zones extending about the theoretical point of engagement of the driven parts and corresponding to the defined angular positions of the driving part, and means operated in each rotation of a driven part to re-set the holding member.

12. In an addressing machine having a driving shaft and at least two driven shafts to be rotated in angular synchronization, the driving shaft having defined drive engagement positions at which driven shafts are operatively engaged by it, a drive control mechanism comprising a coupling for each driven shaft the coupling being such as to make coupling engagement between the driving shaft and its driven shaft only at one of the defined positions of the driving shaft, an electromagnet controlling the operation of each coupling, and means

operated by each driven shaft for controlling each electromagnet as to allow coupling engagement to be made in a synchronization zone extending beyond a selected common synchronizing engagement point of the shafts to be driven for each defined coupling position of the driving shaft, the coupling engagement being effected for each of the shafts to be driven from a rest position at the same defined engagement position of the driving shaft as for driven shafts already in rotation and means for initiating at will the driving of some of the driven shafts ahead of the other driven shafts.

13. In an addressing machine according to claim 4 further comprising operator-controlled selector means related respectively to the driven shafts and an operator-controlled component to render active the coupling of one among the shafts to be driven in accordance with the selection of the selector means.
